UNITED STATES PATENT OFFICE.

FRANK FOY, OF DES MOINES, IOWA, ASSIGNOR TO THE DES MOINES INCUBATOR COMPANY, OF SAME PLACE.

DESIGN FOR A LAMP ATTACHMENT.

SPECIFICATION forming part of Design No. 26,558, dated January 26, 1897.

Application filed November 7, 1896. Serial No. 611,409. Term of patent 7 years.

To all whom it may concern:

Be it known that I, FRANK FOY, a citizen of the United States of America, and a resident of Des Moines, in the county of Polk and State of Iowa, have invented a new and useful Design for Lamp-Burner Attachments, of which the following is a specification.

This invention relates to certain improvements in designs for attachments to lamps whereby a reservoir and pipe leading therefrom may be so shaped and arranged as to feed and supply water from the reservoir to a lamp-burner.

My invention consists in the design herein after set forth, pointed out in my claim, and illustrated by the accompanying drawing, in which the figure illustrates my complete design.

In the design, as shown, the numeral 14 designates a reservoir of cylindrical form. A pipe 15, hollow and angular in cross-section, communicates at its upper end with the bottom of the reservoir. The pipe 15 extends downwardly from the bottom of the reservoir

a considerable distance, is bent laterally at 25 17 at right angles and extends horizontally to one side of the vertical plane of the reservoir a considerable distance, is bent upwardly obliquely at 18 and extends a distance approximately equal to the length of the portion between the bend at 17 and the bottom 30 of the reservoir, and terminates in a laterally-enlarged or bossed open-ended portion 16. The bossed open-ended portion 16 is relatively thin and materially wider than the pipe 15. 35

In practical use of the attachment formed according to the design above described the enlarged open-ended portion of the pipe is contacted with the wick-tube of a lamp-burner. (Not shown.) 40

I claim as my invention—

The design for an attachment for lamp-burners as shown and described.

FRANK FOY.
